Activity.

UNITED STATES PATENT OFFICE.

GEORGE W. PORTER, OF ALLEGHENY, PENNSYLVANIA.

ELEVATOR-CAR-OPERATING DEVICE.

SPECIFICATION forming part of Letters Patent No. 402,277, dated April 30, 1889.

Application filed January 3, 1888. Serial No. 259,635. (No model.)

To all whom it may concern:

Be it known that I, GEORGE W. PORTER, a citizen of the United States, residing at Allegheny, in the county of Allegheny and State of Pennsylvania, have invented certain new and useful Improvements in Elevator-Controlling Devices; and I do hereby declare the following to be a full, clear, and exact description of the invention, such as will enable others skilled in the art to which it pertains to make and use the same, reference being had to the accompanying drawings, which form a part of this specification.

In the accompanying drawings, Figure 1 is a side elevation of my improved device for operating elevators constructed in accordance with my invention. Fig. 2 is a rear elevation of the same. Fig. 3 is a front elevation of that portion of the device projecting into the elevator-car, showing the movement of the operating-lever. Fig. 4 is an enlarged side elevation of the frame attached to the car, which supports the hand-lever shaft and the several parts connected therewith for operating the vertical shaft, together with the shield for removing the braces from the said vertical shaft. Fig. 5 is an end elevation of the same. Fig. 6 is a sectional plan view taken on the line $x-x$. Fig. 7 is an enlarged side elevation of the device used for operating the valves governing the motive power. Fig. 8 shows one of the pins secured at the top and bottom of the elevator-shaft, which acts as an automatic stop for the car when the same reaches its highest or lowest point.

To put my invention into practice, I provide a shaft, a , having a key-seat, b , extending the entire length of the same, and secure this shaft a vertically, in a proper position, in the shaft of an elevator by attaching the top and base of the same in suitably-constructed bearings c , and at regular intervals along the shaft properly-constructed braces d , capable of being moved vertically to allow certain other portions of the device to pass that point without interference. At the base of this vertical shaft a is secured a small bevel gear-wheel, e , which meshes with another, f , attached to a horizontal shaft, g , mounted in proper bearings, h , having a segment of a gear-wheel, i , attached to the opposite end, which

operates a vertical rack, k , connected to the valve governing the motive power used for operating the elevator-car m . Securely attached to the elevator-car m is a frame, n , having two bearings, o , formed on the rear side of the same. These bearings o are provided with suitable caps, p , which afford a means for attaching the frame n to the shaft a and allow the same to move vertically. Loosely attached to the shaft a by means of a spline operating in the key-seat b of the shaft a is a small beveled pinion, q , which meshes with another, r , mounted on a shaft, s , attached to the front side of the frame n . Attached to the end of this shaft s , projecting into the elevator-car m , is a hand-lever, t , which, if moved in either direction, will revolve the shaft a by means of the bevel-gearings q r . A short lever, u , attached to the horizontal shaft s between the gear-wheel r and the frame n , serves to revolve the vertical shaft a when the car m has reached the highest or lowest point in the elevator-shaft by the said lever u meeting an obstruction properly placed at given points in the elevator-shaft. Surrounding this frame on two sides is a shield, w , which, when brought against the above-described braces d from either direction, will move the same to one side.

In operating this device, if the lever t is moved a short distance upward the shaft a is revolved, which operation revolves the gear-wheels e f and shaft g , which opens the valve l for the upward movement of the car m . If a downward movement of the car m is desired, the lever t is revolved below the horizontal center of the same, which movement opens the valve for the downward movement of the car m .

Having thus described my invention, what I claim, and desire to secure by Letters Patent, is—

1. In an elevator-controlling device such as described, the vertical shaft a , having formed along its entire length a key-seat, b , and the same properly secured in a vertical position in an elevator-shaft, the gear-wheel q , operating along the shaft a by means of a spline, z , and mounted in a frame, n , attached to the side of the elevator-car m , and the beveled

15. In a device for operating and controlling elevator-cars, a pinion r , secured to the operating-lever shaft s , whereby the vertical shaft a may be rotated in either direction, as and for the purpose described.

15. 2. In a device for operating and controlling elevator-cars, the vertical shaft a , secured at the top and base in suitable bearings, c , the hinged braces d , and a means for retaining the same in a horizontal position, in combination with a shield or guard, w , secured about the device for operating the shaft a , whereby

the said braces d may be temporarily removed from the vertical shaft, substantially as set forth.

In testimony that I claim the foregoing I 15 hereunto affix my signature this 3d day of November, A. D. 1887.

GEORGE W. PORTER. [L. S.]

In presence of—

C. C. LEE,

H. H. PEARSON.
